IDENTIFICATION PULL TAB FOR SLIDE
FASTENERS

George D. Knoess, New York, N. Y.

Application March 15, 1937, Serial No. 130,809

2 Claims. (Cl. 24—205)

This invention relates to new and useful identifying, stationary or interchangeable pull tab slider plates, which may be plain, jeweled and otherwise ornamented, to be used optionally on different objects fitted with a slide operated fastener.

More specifically the invention contemplates the provision of a stationary or interchangeable pull tab for a slide plate of any description, shape or size to be used on a slide operated fastener of the "zipper" type.

Still further the invention contemplates the provision of a pull tab which may be actually or originally used on a slide plate operated fastener.

Still further the invention proposes a pull tab for the slide body or slide plate of a hookless fastener which is designed for use on various articles such as sport jackets and sweaters, uniform jackets, lumber jackets, wind breakers, dresses, bags and satchels, brief cases, tobacco pouches, galoshes, boots, shoes and leggings or similar articles on which hookless fasteners are used to advantage.

Still further the invention proposes the construction of a pull tab for a slide plate constructed of a material such as metallic or any other substance which has a hardness that permits it to be suitably inscribed by stamping or otherwise marked with identification indicia.

As a further object of the present invention, it is proposed to construct the ordinary pull tab support, which is usually fixedly mounted on the slide plate or body, as commonly known and used on slide fasteners of various manufactures, with a pivot or swivel end to be secured to the upper wing of the slide plate by means of a rivet head which permits freedom of rotation of the pull tab; the other end of said pull tab support is to be eye or loop shaped, to permit the passing through of a leaf spring in conjunction with pull tab; which function is for the purpose to hold, engage or disengage and respectively interchange said pull tab from one object to another.

Still further the invention proposes the construction of a pull tab which may be interchanged between a number of slide fasteners and being suitably initialed, monogrammed, or otherwise inscribed for proving and safe-guarding the ownership of the articles upon which it is used. This interchangeable construction provides for opposed finger portions which are pivotally mounted on the slider plate and which may be

engaged in the loop portion on the face of the slide body.

Still further the invention provides for a leaf spring to be either in one piece with, or to be fixedly mounted on the underside of the pull tab which may be optionally and alternately engaged in the looped support member on said slide plate on any of the hookless fastener types for releasably holding the pull tab in position.

A further provision of the invention is to provide a pull tab consisting of a bottom section suitably inscribed, and a top section releasably connected to the bottom section and being provided with a window opening through which the engraved portion may be viewed.

As a further object of the invention it is proposed to construct the pull tab of various shapes, designs, and sizes which may be either originally mounted on the slide plate or which may be interchangeable between a number of slide plates.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a fragmentary front view of a "zipper" having a pull tab constructed according to this invention.

Fig. 2 is a front view of a garment having a modified form of pull tab.

Fig. 3 is a front view of another type of pull tab.

Fig. 4 shows a perspective view of another pull tab constructed according to a still further modification of the invention.

Fig. 5 is a still further modified form of the invention.

Fig. 6 is a further modified form showing a pull tab with an ornamented shape, and initials.

Figs. 7-10 inclusive show still further modified forms of pull tabs used in conjunction with various articles.

Fig. 11 is a further modified form of the invention.

Fig. 12 is an enlarged sectional view taken on the line 12—12 of Fig. 11.

Fig. 13 is a detailed sectional view taken on the line 13—13 of Fig. 11.

Fig. 14 shows another modification of the invention.

Fig. 15 is a sectional view taken on the line 15—15 of Fig. 14.

Fig. 16 is a fragmentary perspective view partly in section, illustrating another embodiment of the invention.

Fig. 17 is a perspective bottom view of another modification of this invention, showing an identification pull tab which also may be used in connection with the arrangement shown in Fig. 16.

The stationary or interchangeable, plain or ornamented identification pull tab in Fig. 1, according to this invention, is associated with a body portion 10 of a garment or similar article on the open sides of which there is mounted rows of "zipper" or slide fastener elements 11. A slide plate 12 is associated with the "zipper" elements 11 and is adapted to be moved to open or close them. The slide plate 12 consists of the usual slide body 12^a and a looped support 12', which is for the purpose to interchangingly receive and hold a leaf spring extending from the pull tab 13 and engaging in looped portion of support 12'. Said pull tab support 12' is rotatably mounted on the slide body 12^a to permit rotation of said support 12', thus giving to said pull tab a rotary and pivotal function or more specifically a double action in its movement. A suitable identification mark 14 is provided upon the faces of the pull tab 13 which pivotally engages the looped support 12' of the slide plate 12 and is to be used to properly identify the article on which such pull tab 13 is mounted in conjunction with the slide fastener. This identification mark 14 may be an initial or any similar group of initials or identification marks which would serve to show the ownership of the article.

According to the modification shown in Fig. 2 the front portion of a garment 15 is shown. On the open edges thereof hook fasteners 11 are mounted and a slide plate 12 is associated therewith for opening and closing the element 11. The pull tab 18 is constructed with the leaf spring 47^a and comprises a piece of metal or any other material such as Celluloid, Bakelite, Pyroxylin, etc., having an oval contour and provided with suitable identification markings 19 along the length thereof.

In the modification shown in Fig. 3 a circular pull tab 20 is associated with a slide plate 12 which is used to open or close a row of zipper elements 11. The pull tab 20 constructed with a leaf spring 47^a is of circular shape and is provided with a suitable identification mark 23.

In the modification shown in Fig. 4 it will be noted that the pull tab 20 shown in Fig. 3 may be constructed of different shapes and material and be suitably provided with identification marks 24, also the leaf spring 47^a, the rotatably mounted support 12' on the slide plate 12^a is shown.

According to the modification of the device shown in Fig. 5 a triangular pull tab 25 is provided with a suitable identification mark 26 running parallel with the hypotenuse of the triangular element 25. This triangular element 25 is associated with a slide plate 12 for opening and closing the "zipper" elements 11.

In the modification shown in Fig. 6 a pull tab 30 is shown which has a contour of a plant leaf and which is impressed with markings 31 representing the veins of the leaf. In connection with this form of pull tab it is pointed out that the tab 30 may have any desired ornamental shape and be initialed or monogrammed and decorated with suitable material or markings which would harmonize with the chosen shape.

In the modification shown in Fig. 7, a pull tab

35, is shown which has an elongated commonly known and used shape and is provided by suitable processes with the name, address or similar legend 36 which may be used to identify a brief case, bag, or similar article which might be carried in one's hand, or be in one's possession.

In Fig. 8 a modified form of pull tab 40 is illustrated which may be used in conjunction with clothing and which has suitable markings 41 for the purposes of identification.

In Fig. 9 a commonly known and used pull tab 45 constructed with a leaf spring 47^a according to this invention is shown which is suitably provided with the initials 46 of the person wearing or otherwise possessing the object upon which it is used.

In Fig. 10 a pull tab 47 is shown with the downwardly projecting extension 47' which forms a resilient leaf spring 47^a, held against the bottom face 47^b of the pull tab 47. The free end 47' of the resilient extension 47' is turned away from the bottom face 47^b to permit easy engagement of the loop over the loop portion 12' on a slide plate 12^a.

According to the modification shown in Figs. 11-13 a pull tab 50 is shown which consists of a bottom section 50^a and a top section 50^b. The bottom section 50^a is suitably inscribed with identification marks 51 and is viewable through a window opening 52 in the top section 50^b. A piece of glass 53 or similar translucent material is mounted in the window opening 52 to protect the engraved portion 51 on the bottom section 50^a.

A means is associated with the inner end of the top section for releasably engaging the pull tab on to the support loop of the slide plate 12 of a "zipper". This means includes a pair of opposed finger portions 54 which are pivotally mounted on the edge of the top section 50^b by means of pintle pins 55. One of the opposed finger portions 54 is provided with an opening 56 through which a screw 57 may be engaged. This screw 57 threadedly engages an opening 58 on the opposed finger portion 54 to hold the finger portions 54 in position when the pull tab 50 is mounted on the support loop of the slide plate. Screws 59 freely engage through the bottom section 50^a and threadedly engage the top section 50^b for holding these sections together.

The operation of the device is as follows:

When it is desired to position the pull tab 50 on the slide plate of a "Zipper" it is merely necessary to remove the screw 57 from the opening 58 in one of the opposed fingers 54 to permit these fingers to be pivoted. The fingers 54 are then pivoted outwards to permit them to be disengaged from the loop portion formed on the slide plate. These fingers 54 are then pivoted to their normal position and the screw 57 returned to its normal position within the opening 58 to hold the pull tab 50 on the loop portion of the slide plate. The operation is the same as described above when it is desired to change this pull tab 50 from one slide plate to another.

According to the modification shown in Figs. 14 and 15, a pull tab 60 is provided upon one of its faces 60^a with a suitable identification mark 61 and has an inner end 60^b where a pin 62 engages through one end of a curved leaf spring 63 to hold the leaf spring in fixed position on the bottom face 60^c of the pull tab 60. The other end 63^a of the leaf spring 63 is turned away from the bottom face 60^c to permit the leaf spring to be easily engaged over the loop portion 12' on the slide plate 12^a.

The operation of the device as shown in Figures

1 to 10, 16 and 17, is as follows: When it is desired to position the pull tab to a slide plate it is merely necessary to engage the free end of the leaf spring 47^a into the loop portion 12' of the slide body 12^a, and simultaneously press inwards to cause the loop portion to pass the abutting sides of the leaf spring 47^a and the pull tab. The resiliency of the leaf spring 47^a is depended upon to hold the pull tab in position thereon.

10 In Figs. 16 and 17 the pull tab support 65 is rotatably secured to the upper wing 12^b of the slide body 12^a by a retaining neck 66 which is riveted at 67 to form a head so as to permit rotation of the support 65. Above its axis this pull tab support is eye or loop shaped constructed and is adapted for the interchanging purpose of releasably engaging and holding a pull tab in place for operation; the free end of said pull tab support may be formed if so desired with a spherical head 68 of snap fastener type and is adapted to be engaged by a complementary (female) snap fastener member 70 on the pull tab 71. These arrangements permit a pivoting and rotating movement of the pull tab and thus effecting a front exposure of the pull tab at all times whether same is operated for closing a hookless fastener by upward or downward movement. When it is desired, the pull tab 71 may be kept in aligning position by engaging a post 72 which protrudes 20 symmetrically from the pull tab 71, into notch or cavity 69 in the upper wing 12^b of the slide plate 12^a.

25 The pull tab 71 is provided with initials 73 or

other personal symbols and may be otherwise inscribed for the definite purpose of personal identification of slide fastener operated objects fitted with said pull tab.

While I have illustrated and described the preferred embodiments of my invention, it is to be understood that I do not limit myself to the precise constructions herein disclosed and the right is reserved to all changes and modifications coming within the scope of the invention as defined in 10 the appended claims.

Having thus described my invention, what I claim as new, and desire to secure by United States Letters Patent is:—

1. A slider for fasteners of the class described comprising a plate member, a pull tab member and means for removably mounting said tab on said plate member, said means comprising cooperative snap fastener elements on said tab and plate members, respectively, a pin on one of said 15 members, the other of said members having a complementary notch therein for engagement with said pin, whereby to prevent rotation of either of said members relative to the other.

2. A slider as claimed in claim 1, said pull tab 25 member having indicia thereon, said pin being on said tab, said notch being in said plate member, said pin and notched member, when engaged, being adapted and arranged to hold said indicia in a pre-selected angular position relative to said 30 fasteners.

GEORGE D. KNOESS.
